LOCOMOTIVE FRONT END

Leslie R. Pyle, Chicago, Ill., assignor to Locomotive Firebox Company, Chicago, Ill., a corporation of Delaware

Application May 28, 1943, Serial No. 488,823

11 Claims. (Cl. 230—97)

This invention relates to improvements in locomotive front ends and more particularly to those embodying a circumferentially open, centrifugal spark arrester in the smoke box and it consists of the matters hereinafter described and more particularly pointed out in the appended claims. For a locomotive front end of this kind, reference is made to my prior Patent 2,244,726 of June 10, 1941.

One of the objects of the present invention is to provide a locomotive front end structure of this kind which may be said to be self-cleaning in that the heavier cinders and the like, which are deflected from a direct path leading into the spark arrester and therefore drop or fall to the bottom of the smoke box, are caused to pass through the arrester from below and are entrained with the nozzle blast for discharge up and out through the stack.

A further object of the invention is to provide a locomotive front end structure that includes but a few baffle elements therein and which are so disposed as to present a minimum of resistance to the movement of the products of combustion through the same so that a better draft action is afforded.

Also, it is an object of the invention to provide a locomotive front end structure in which the heavier live sparks, after falling to the bottom of the smoke box, are delayed in their movement to the point of discharge into the stack, for a period which assures that said sparks are extinguished before they are entrained into the stack for discharge therefrom.

Furthermore, it is an object of the invention to provide in a locomotive front end structure, a novel deflector vane arrangement for the arrester which makes the arrester more positive in its action in preventing the entrance of heavier live sparks thereto and causes them to fall to the bottom of the smoke box for extinguishment before they are drawn into the stack for discharge.

The above mentioned objects of the invention, as well as others, together with the several advantages thereof, will more fully appear as the specification proceeds.

In the drawings:

Fig. 1 is a longitudinal vertical sectional view through a locomotive front end embodying the preferred form of the invention.

Fig. 2 is a horizontal sectional view through the front end structure appearing in Fig. 1 as taken on the line 2—2 thereof.

Fig. 3 is a transverse vertical sectional view

through the improved locomotive front end on a scale somewhat enlarged over that of Fig. 1 and as taken on the line 3—3 of said Fig. 1.

Fig. 4 is a perspective view of an improved form of deflector vane employed in a part of the arrester that is included in the front end.

Fig. 5 is a perspective view of a certain truncated conical tubular member embodied in the improved front end structure for use in connection with the nozzle for causing the heavier products of combustion at the bottom of the smoke box shell to enter the stack.

Referring now in detail to that embodiment of the invention illustrated in the drawings, 10 indicates the tubular body of a locomotive smoke box shell which is connected at its rear end to the front end of the boiler shell 11 in the conventional manner. The interior of the smoke box shell is separated from the interior of the boiler shell 11 by a flue sheet 12. Flues 13 open through the sheet 12 so as to discharge products of combustion into the interior of the smoke box shell. In Fig. 1 only one of said flues is shown and this is in dotted lines. 14 indicates the front for the smoke box shell, which is provided with the usual door. At the bottom of and inside of the body of the smoke box shell is a floor plate 15.

16 indicates the flanged base for the smoke stack, which base is directly attached to the top of the body 10 of the smoke box shell about an opening 17 therein. Said smoke stack has a tubular extension portion 18 fixed to its bottom end and said tubular portion depends into the interior of the body of the smoke box shell and is adapted for the attachment of a lift pipe thereto as will appear later.

The exhaust pipe, which is indicated at 19, rises from the bottom of the body 10 of the smoke box shell in axial alignment with the tubular portion 18 of the stack. Said exhaust pipe, which is relatively short, is provided at its top end with an exhaust nozzle or tip 20 of any approved kind.

In the body 10 of the smoke box shell is located 45 a spark arrester of the so-called circumferentially open centrifugal type and the same is indicated as a whole at 21. Such an arrester, which is cylindrical in shape, has its axis arranged in alignment with the axes of the tubular portion 18 of the stack and the tip or nozzle 20 of the exhaust 19 respectively.

The spark arrester 21 comprises vertically spaced top and bottom plates 22 and 23 respectively and sets of front and rear perpendicular vanes or deflector plates 24 and 25 respectively.

which are fixed at their ends to the top and bottom plates 22 and 23 respectively. The vanes 24 of the front set are shown as plain flat plates. The vanes 25 are also flat plates but are each provided on opposite sides toward but spaced different distances from the outer end thereof with right angled deflector wings 25a and 25b respectively. One of said vanes appears in perspective in Fig. 4.

While the deflector plates 24 and 25 just above mentioned are shown in Fig. 2 as plain flat plates and straight transversely, they may be made so as to have some curvature transversely. They are disposed tangentially and extend inwardly from the outer circle of the top and bottom plates 22 and 23 of the arrester 21 to terminate short of the circle of the lift pipe 26. The purpose of the use of different kinds of deflector plates or vanes in the sets 24 and 25 thereof will appear later.

The bottom plate 23 of the arrester engages in supporting relation upon transversely extending bars 27-27, the ends of which are suitably fixed to parts of the body 10 of the smoke box shell. The lift pipe 26 extends through a central opening in the top plate 22 and projects a suitable distance into the upper end of the arrester 21. Preferably the top plate 22 is made as front and rear detachably connected semi-circular parts for installation purposes so that it is unnecessary to dismantle the stack to permit installation. Said top plate is provided with a flanged ring 28 about the opening before referred to, to provide a better engagement for the lift pipe 26.

Within the upper portion of the interior of the arrester 21 is located another set of deflector vanes 29 of an auxiliary character and which are supported from the bottom end of said lift pipe 26. While this set of deflector vanes forms no part of the present invention, so as to require a detailed illustration or description thereof, it is mentioned in passing that they, too, are disposed tangentially and extend in a direction opposite that of the deflector vanes 24 and 25 previously referred to. However, the purpose of the vanes 29 will be mentioned later.

With the arrangement described, room or space is present at opposite sides of the arrester 21 for the passage of steam pipes 30, which lead to the cylinders of the locomotive, of which the smoke box shell forms a part. These pipes have a flanged upper end connection with superheater headers 31 located in the upper rear portion of the smoke box shell. Said pipes and superheater headers, as well as the superheater tubes 32 best appear in dotted lines in Figs. 1 and 3 of the drawings.

33 indicates a truncated hollow cone-like member associated with the exhaust pipe for ejecting heavier particles of the products of combustion that accumulate upon the floor plate 15. This member, which appears in perspective in Fig. 5, is tubular and is so disposed as to surround the upper portion of the exhaust pipe 19 with its smaller diameter end located in the arrester 21 and with its larger diameter end located below the bottom plate 23 but spaced a suitable distance above the plate 15 as best appears in Fig. 1. As is obvious from Fig. 1, the member 33 defines an annular space 34 around the exhaust pipe and the top end thereof opens into the interior of the arrester while the bottom end of said space opens into the interior of the body 10 of the smoke box shell a short distance above the floor plate 15. The member 33 may be secured in place in any suitable manner. One convenient way is to weld

the member 33 to said plate as indicated at 35 in Fig. 1.

To prevent a too free passage of the used combustion material, such as live sparks on the floor plate, into the bottom end of the space 34 during the operation of the locomotive of which the front end forms a part, I provide a novel baffle arrangement. Said baffle arrangement is so located and its parts are so disposed as to delay the passage of said material to said space until they have become extinguished and this without interfering substantially with the draft action of the locomotive. The baffle arrangement mentioned is located between the bottom plate 23 of the arrester and the floor plate 15. It comprises front and rear baffles 36 and 37 and pairs of intermediate baffles 38 and 39 respectively, all of said baffles engaging at their top and bottom ends with said plates 23 and 15 respectively. The front baffle 36, which is made on an arc concentric with the axis of the arrester, extends laterally each way from the center line of the boiler as a whole. The rear baffle plate is made on an arc having its center disposed rearwardly of the axis of the arrester and it extends laterally each way from said center line. The intermediate baffles 38-38 are made on an arc concentric with the axis of the arrester but on a radius less than that of the baffle 36 and are somewhat less than 90° in extent so as to leave a passage 38a to the rear of the baffle 36. The other baffles 39-39 are made concentric with the baffle 37 and on substantially the radius of the baffles 38. The baffles 39-39 are somewhat less than 90° in extent so as to leave a passage 39a to the front of the baffle 37. Each baffle 39 includes an extension 40 that terminates in a forwardly extending wing 41. The extension 40 of said baffles and associated wings 41 coat with the associated ends of the baffles 38 in forming side passages 42-42 respectively. Thus the baffles mentioned, and which best appear in dotted lines in Fig. 2, provide a maze-like arrangement of passages which lead from the interior of the body 10 of the smoke box shell toward the bottom end of the space 34.

In the operation of the locomotive of which the construction above described forms a part, the products of combustion enter the interior of the body 10 of the smoke box shell, from the flues 13 under the draft action of the jet discharged from the nozzle 20 of the exhaust pipe 19. Such products of combustion vary in size, some being relatively fine and light in weight and others being relatively heavy and in the form of cinders, some of which may be in a glowing state in the form of sparks. As the products of combustion enter the body of the smoke box shell, they travel in a substantially horizontal plane toward the front end 14 and its door. In the discharge of the jet from the nozzle 20 up the stack, a subatmospheric condition is established so that the lighter and extinguished particles of the products of combustion pass through the passages between the vanes 24 and 25 to enter the arrester 21 and be entrained for passage up and out through the stack. In this movement of said particles, the vanes 24 and 25 impart a whirling action to them in one direction. However, as the auxiliary vanes 29 are opposed to the vanes 24-25, said auxiliary vanes tend to counteract said whirling action so that said particles are directed back toward and into the blast for entrainment out through the stack.

However, as to the heavier particles, certain of them will try to directly enter the passageways 75 between the vanes 25 of the rear set and will im-

pinge against the wings 25a—25b and then fall upon the bottom plate 15. Those heavier particles that sail over the top of the arrester 21 will impinge against the front end 14 and its door to then fall or drop upon said bottom plate.

Under the blast action of the nozzle, an aspirating action is induced at the bottom of the space 34, whereby the larger particles of combustion in the vicinity thereof are entrained into the bottom of said space 34 to join the blast as it issues from the nozzle so as to enter the same and be carried out the stack thereby. By reason of the cone or taper shape of the member 33, its side wall directs said particles inwardly toward said blast for a better entrainment therewith.

In the movement of the locomotive in its travel along the track rails, some vibration is present and this will cause the heavier particles of combustion on the bottom plate 15, outside of the baffles 36—37—38 and 39, to dance or hop as they enter the maze-like passages produced by said baffles. As the particles of products of combustion adjacent the bottom end of the space 34 enter said space, others approach said space so that they may be said to crawl toward said space. This dancing or hopping of said particles not only delays the entrance of said particles into the vicinity of the bottom of said space, but it produces an attrition between said particles not only to wear them down in size but to extinguish such particles as may be glowing when they fall upon the bottom plate 15.

Thus, the member 33 provides not only a means which makes the front end substantially a self-cleaning one, but it also provides spark arresting qualities in addition to those of the arrester 21 itself. With the arrangement of parts described, the front end approaches the so-called long desired "empty" front end because though baffles are employed, they are so designed and located as to permit a substantially free draft action.

While in describing the invention I have referred in detail to the form, arrangement and construction of the parts involved, the same is to be considered only in the illustrative sense so that I do not wish to be limited thereto except as may be specifically set forth in the appended claims.

I claim as my invention:

1. In combination with the smoke box shell of a locomotive boiler, means providing a spark arrester including a casing in said shell, a smoke stack having a portion arranged in said shell and operatively disposed with respect to the upper portion of the casing, an exhaust nozzle opening through the bottom of said shell and arranged to discharge into the lower portion of said casing, and means surrounding a portion of said nozzle in a manner defining a space therearound and which space communicates at its top end with the interior of the casing and at its bottom end with an interior part of the smoke box shell above its bottom, at that elevation wherein said means cooperates with the blast action of said nozzle in causing movement of the products of combustion resting on the bottom of said shell, into and up through said space into said casing for entrainment up and out through the stack.

2. In combination with the smoke box shell of a locomotive boiler, means providing a spark arrester including a casing in said shell, a smoke stack having a portion arranged in said shell and operatively disposed with respect to the upper portion of the casing, an exhaust nozzle opening through the bottom of said shell and arranged to

discharge into the lower portion of said casing, and means surrounding a portion of said nozzle in a manner defining a space therearound and which space communicates at its top end with the interior of said casing and is open at its bottom end so as to communicate with an interior part of the smokebox shell above its bottom, at that elevation wherein said means cooperates with the blast action of said nozzle in causing movement of the products of combustion resting on the bottom of said shell into said space from its open bottom end and then up through said space into said casing for entrainment up and out through the stack.

3. In combination with the smoke box shell of a locomotive boiler, means providing a spark arrester including a casing in said shell, a smoke stack having a portion arranged in said shell and operatively disposed with respect to the upper portion of the casing, an exhaust nozzle opening through the bottom of said shell and arranged to discharge into the lower portion of said casing, and a frustro conical tubular member surrounding a portion of said nozzle and defining an annular space therearound which communicates at its smaller top end with the interior of said casing and communicates at its larger bottom end with an interior part of the boiler shell above its bottom, said means cooperating with the blast action of said nozzle in causing movement of the products of combustion resting on the bottom of said shell into and up through said space into said casing for entrainment up and out through the stack.

4. In combination with the smoke box shell of a locomotive boiler, means providing a spark arrester including a casing in said shell, a smoke stack having a part arranged in said shell and operatively disposed with respect to the upper portion of the casing, an exhaust nozzle opening through the bottom of the shell and having a discharge tip disposed within the lower portion of said casing, and tubular means surrounding a portion of the nozzle in a manner defining a space therearound, the top end of said means extending into said casing to an elevation above that of the tip of said nozzle, said space having communication at its bottom with an interior part of the boiler shell above its bottom, said means cooperating with the blast action of said nozzle in causing movement of the products of combustion resting on the bottom of said shell into and up through said space into said casing for entrainment up and out through the stack.

5. In combination with the smoke box shell of a locomotive boiler, means providing a peripherally open centrifugal spark arrester embodying therein top and bottom plates and deflector vanes disposed between marginal parts of said plates, a smoke stack having a portion arranged in said shell with its bottom end disposed in operative relation to said top plate, an exhaust nozzle opening through the bottom of said shell and having an upper end arranged to discharge into the arrester, and means surrounding a portion of said nozzle in a manner defining a space therearound, said means having a sealed connection at its mid portion with said bottom plate to leave top and bottom end portions disposed above and below said bottom plate, said bottom end portion being formed to have communication with an interior part of the smoke box shell above its bottom, said means cooperating with the blast action of the nozzle in causing movement of products of combustion resting on said bottom of the

shell into and up through said space into the arrester for entrainment up and out through the stack.

6. In combination with the smoke box shell of a locomotive boiler, means providing a spark arrester including a casing in said shell, a smoke stack having a portion arranged in said shell and operatively disposed with respect to the upper portion of the casing, an exhaust nozzle opening through the bottom of said shell and arranged to discharge into the lower part of said casing, means surrounding a portion of said nozzle in a manner defining a space therearound and which space communicates at its top end with the interior of the casing and at its bottom end with an interior part of the smoke box shell, said means cooperating with the blast action of said nozzle in causing movement of the products of combustion resting on the bottom of said shell into and up through said space into said casing for entrainment up and out through the stack, and other means disposed between the bottom of the casing and said bottom of said shell and surrounding the first mentioned means for providing tortuous passageways for said product of combustion before they enter said space.

7. In combination with the smoke box shell of a locomotive boiler, means providing a spark arrester including a casing in said shell, a smoke stack having a portion arranged in said shell and operatively disposed with respect to the upper portion of the casing, an exhaust nozzle opening through the bottom of said shell and arranged to discharge into the lower portion of said casing, and a truncated tubular member surrounding a portion of said nozzle and defining an annular space therearound, the upper smaller diameter end of said member being disposed within said casing and the lower larger diameter end of said member being arranged in spaced relation above the bottom of said smoke box shell, said member cooperating with the blast action of said nozzle in causing movement of the products of combustion resting on said bottom of said shell into and up through said space into said casing for entrainment up and out through the stack.

8. In combination with the smoke box shell of a locomotive boiler, means providing a spark arrester including a casing in said shell, a smoke stack having a portion arranged in said shell and operatively disposed with respect to the upper portion of the casing, an exhaust nozzle opening through the bottom of said shell and arranged to discharge into the lower portion of said casing, and means surrounding a portion of said nozzle in a manner defining a space therearound and which space communicates at its top end with the interior of the casing and at its bottom end with an interior part of the smoke box shell above its bottom, said means cooperating with the blast action of said nozzle in causing movement of the products of combustion resting on the bottom of said shell, into and up through said space into said casing for entrainment up and out through the stack, and a plurality of baffles arranged between the bottom of the casing and the bottom of said shell, with the ends of certain of said baffles overlapping and spaced from each other to form a space about said nozzle having a tortuous passage communication with the bottom space of the boiler shell surrounding said baffles.

9. In combination with the smoke box shell of a locomotive boiler, means providing a spark arrester including a casing in said shell, a smoke stack having a portion arranged in said shell and operatively disposed with respect to the upper portion of the casing, an exhaust nozzle opening through the bottom of said shell and arranged to discharge into the lower portion of said casing, and a truncated tubular member surrounding a portion of said nozzle and defining an annular space therearound, the upper smaller diameter end of said member being disposed within said casing and the lower larger diameter end of said member being arranged in spaced relation above the bottom of said smoke box shell, said member cooperating with the blast action of said nozzle in causing movement of the products of combustion resting on said bottom of said shell into and up through said space into said casing for entrainment up and out through the stack, and a plurality of curved baffles arranged between the bottom of the casing and the bottom of said shell, with the ends of certain of said baffles overlapping and spaced from each other to form a space about said nozzle having a tortuous passage communication with the bottom space of the boiler shell surrounding said baffles.

10. In combination with the smoke box shell of a locomotive boiler, means providing a spark arrester including a casing in said shell comprising top and bottom horizontally disposed plates and vertical vanes extending between said top and bottom plates and having spaces therebetween for the passage of products of combustion from the interior of said shell into the interior of said casing, means associated with certain of said vanes and extending laterally therefrom into said spaces to function as baffles as well as to define tortuous passages therethrough, a smoke stack having a part arranged in said shell and operatively disposed with respect to the upper portion of said casing and an exhaust nozzle arranged to discharge into the lower portion of said casing.

11. In combination with the smoke box shell of a locomotive boiler, means providing a spark arrester including a casing in said shell comprising top and bottom horizontally disposed plates and vertical vanes extending between said top and bottom plates and having spaces therebetween for the passage of products of combustion from the interior of said shell into the interior of said casing, means associated with certain of said vanes and extending laterally therefrom into said spaces to function as baffles as well as to define tortuous passages therethrough, a smoke stack having a part arranged in said shell and operatively disposed with respect to the upper portion of said casing, an exhaust nozzle arranged to discharge into the lower portion of said casing, and means surrounding a portion of said nozzle in a manner leaving a space therearound and which space communicates at its top end with the interior of said casing and at its bottom end with an interior part of the smoke box shell above its bottom, said means cooperating with the blast action of the nozzle in causing movement of the products of combustion resting at the bottom of said shell into and up through said space into said casing for entrainment up and out through the stack.

LESLIE R. PYLE.
